UNITED STATES PATENT OFFICE.

JOHN F. CLANCY, OF CHICAGO, ILLINOIS, ASSIGNOR TO KAESTNER & HECHT COMPANY, OF CHICAGO, ILLINOIS, A CORPORATION OF ILLINOIS.

ELEVATOR-DOOR LOCK.

Application filed June 22, 1922. Serial No. 570,219.

To all whom it may concern:

Be it known that I, JOHN F. CLANCY, a citizen of the United States, residing at Chicago, in the county of Cook and State of Illinois, have invented a certain new and useful Elevator-Door Lock, of which the following is a specification.

My invention relates to improvements in safety locks and particularly to such locks as are used on elevator hatchway doors.

Some elevator hatchways are so constructed that the doors thereto can be opened from the exterior, or can be opened by anyone regardless of the position of the cage. It also happens that at times an elevator operator may not completely close the door when leaving the associated landing, thereby making it possible for anyone to gain admittance to the hatchway. In both of the above instances a condition exists which is undesirable because it is not conducive to safety.

One of the objects of my invention therefore is to provide means whereby the cage is prevented from moving unless all hatchway doors are closed and securely locked.

A further object of my invention is to provide means whereby the opening of any hatchway door is prevented unless the cage is standing level with that particular floor.

Another object is to provide a safety device whereby the opening of any hatchway door is prevented while the cage is in motion.

A further object is to provide a lock for elevator doors which is magnetically controlled and which necessitates no movement of parts to allow the door to be opened, thereby being noiseless in operation and avoiding the use of springs, tumblers or other moving elements.

Still another object is to provide a lock for elevator doors which is held in an unlocked position by means carried by the cage and which makes no mechanical connection with the hatchway.

A further object is to provide a lock which comprises a switch in one of the essential circuits of the elevator control system, said switch being opened and closed by opening and closing the adjacent hatchway door.

An important object is to provide a lock which will prevent reopening of the door even though the latter is only partially closed.

Another object is to provide a lock which has manually operable means whereby the door can be opened in case of emergency,

such as when the current is shut off or the magnetic controlling means fails to function.

A further object is to provide a lock with an auxiliary electromagnet adapted to be excited by means of a special circuit whereby the lock will be held inoperative so that the door can be opened, said special circuit being such that only authorized persons can close it.

A final object is to provide a lock for elevator doors which is sturdy and simple in construction, and which can be easily and cheaply installed.

Other objects and advantages of my invention will become apparent as the description proceeds.

The objects of the invention thus generally stated are attained by the construction and arrangement illustrated in the accompanying drawings forming part hereof, wherein:

Fig. 1 is a diagrammatic representation of an elevator control system with several of the locks shown as forming part thereof.

Fig. 2 is a sectional view of the lock with the door plunger partly withdrawn and in a locked position.

Fig. 3 is a sectional view of the lock with the adjoining door completely closed.

Fig. 4 is a perspective view showing the relative position of the lock and the electromagnet for controlling its action.

Fig. 5 is a vertical sectional view of the lock taken in the plane of the line 5—5 of Fig. 3.

Fig. 6 is a fragmentary sectional view of the locking collars showing their bores in alignment, but with the door plunger removed.

Fig. 7 is a sectional view of the lock taken in the plane of line 7—7 of Fig. 3.

Fig. 8 is a sectional view of the lock taken in the plane of line 8—8 of Fig. 3.

Fig. 9 is a perspective view of the locking collar.

Fig. 10 is a view partly in section showing a lock which is equipped with an auxiliary electromagnet and which is adapted to receive the plunger of a door which closes to the left.

To illustrate my invention, I have shown the preferred embodiment thereof as forming part of an elevator system in which the necessary wiring connection for its inclu-

110

sion have been made. It is to be understood, however, that the invention can be adapted for use with any other type of elevator system.

5 In general, the elevator cage 1 having a counterweight 2 which is connected thereto by a cable 3 is caused to travel by a drum 4 which in turn is driven by the motor 5. A circuit through the motor armature 6 is connected across the main line terminals L plus and L minus, and is adapted to be closed by either the "down" electromagnetic switch 7 or the "up" electromagnetic switch 8. Each switch is controlled by a 10 separate actuating circuit which is subject to be closed by the control device 9 in the cage. Said control device when not closing one of the actuating circuits, acts to close a circuit through the electromagnet 10. 15 Door locks 11 are secured to the hatchway adjacent each door, and are included in both actuating circuits as switches which are closed by plungers 12 carried by each door. Each lock is so constructed that the plunger 20 cannot be withdrawn except when the electromagnet 10 carried by the cage is positioned adjacent thereto. Although the invention as herein illustrated is shown as using direct current, it is to be understood 25 that it can readily be adapted to use alternating current.

The motor 5 in the present instance is separately and permanently excited by the field winding 13 which is connected directly 30 across the main line terminals, L plus and L minus, and is subject to the action of the brake 14, the latter being excited by the coil 15. The motor 5 rotates the drum 4 in either direction through the worm 16 and worm wheel 17, depending upon the direction of flow of the current through the armature 6.

The control device 9 comprises two side contacts 18 and 19, a central contact 20, and 45 a segmental contact 21 pivoted at 22 and connected to the minus main of the line. The segmental contact 21 in effect forms part of the actuating lever 23 which is also pivoted at 22.

50 In moving the segmental contact 21 to the right into engagement with contact 18 the actuating circuit for the down switch 7 will be closed provided no hatchway door is open. The circuit can be traced as follows: from the plus main, through wire 24 and the door locks 11, solenoid 25, wire 26, contact 18, contact 21, and wire 27 to the minus line. Excitation of the solenoid 25 will cause the core 28 of the "down" switch 7 to ascend thereby closing three sets of contacts 29, 30 and 31.

55 By closing the contacts 29, the circuit through the coil 15 is connected across the main line terminals, thereby removing the action of the brake 14 from the main drive

shaft 32 of the motor 5 so that the latter is free to operate. Closing the contacts 30 and 31 acts to close a circuit through the motor armature 6, which can be traced as follows: from the plus main through resistance 33, arm 34, wire 35, contacts 31, wire 36, armature winding 6, wire 37, and contacts 30, to the minus main of the line. A parallel circuit shunting the armature 6 is also closed, said circuit being traced as follows: from the contacts 31, through wire 39, solenoid 38, wire 40, and wire 37 to contacts 30. The solenoid 38 is provided with a core 41 which is connected at one end to the arm 34 and at the other end to the piston 42 of a dashpot 43. The arm 34 when being forced up by the core 41 gradually reduces the resistance 33 in the armature circuit. The dashpot prevents the core from moving upward too rapidly but allows it to drop quickly. Thus when the solenoid is excited, the resistance in the armature circuit will be progressively reduced until the motor 5 is operating at full speed.

55 If the segmental contact 21 is swung to the left into engagement with contact 19, the electromagnetic switch 8 will operate to close the circuit through the motor armature 6 but with its terminals reversed so that the motor 5 will operate in the opposite direction. The resistance 33 will again be gradually reduced to bring the motor up to full speed.

In the exemplary form herein disclosed, the elevator door locks 11 in general comprise individually a plurality of locking elements which in the present instance are collars 44, 45 and 46, a switch 47, a casing 48 for housing and supporting said elements, and the plunger 12 carried by the door 49 and adapted to enter said lock to be retained thereby, and to close said switch 47, which forms part of the actuating circuits for the "up" and "down" electromagnetic switches. The casing 48 may be of any suitable form or construction. In the present instance, I have shown the casing as having a bracket formed integral therewith by means of which it is secured to the hatchway adjacent the door 49.

115 The collars 44 and 45 are secured in opposite ends of the non-magnetic shell 50 which is screwed into one end of the casing 48. The locking collar 46 which has one side cut at an angle is held loosely between the collars 44 and 45, and is prevented from rotating by a projection 51 which enters a notch 52 in its periphery. A finger 53 extending through an elongated slot 54 in the shell 50 is secured to the reduced edge of the collar 46, and constitutes an emergency release for the lock.

120 The switch 47 consists of a pair of contacts 55 which are pivoted to an insulating collar 56, and which are adapted to be 130

closed by a magnetic point 57 mounted on and insulated from the plunger 12. The contacts 55 are provided with free ends, which are shaped to conform to the surface 5 of the point 57, and which are pressed toward said point by springs 58 so as to insure a good electrical connection. Any suitable contacts adapted to resiliently engage the point 57 may be employed. Leads 59, which 10 enter the casing 48 through a conduit 60, are secured to the contacts by suitable binding posts 61.

The collars are all provided with central bores which register with each other when 15 the locking collar 46 is held in an upright position against the inner face of collar 44. The plunger 12 is of a diameter slightly less than that of the bore so as to allow it to enter freely, and has on its peripheral surface 20 a pair of triangular grooves 62 and 63, the outer end faces of which are in a plane perpendicular to its axis so as to constitute shoulders 64 and 65. It will be seen that the plunger can enter the lock regardless of the 25 position of the collar 46, and that when once in it will hold the latter in its upright position. However, in withdrawing the 30 plunger by starting to open the door, the notch 63 will be moved to underlie the locking collar 46 which will be tilted out of alignment with the other collars by friction and its own weight, so that the shoulder 65 will engage the flange 66 to prevent further 35 opening of the door. The point 57 is of sufficient length so that the circuit through the contacts 55 will not be broken by this 40 partial withdrawal of the plunger. If the door is only partially closed to the point where the notch 62 underlies the collar 46, shoulder 64 will prevent it from being reopened. The points 57, however, in this 45 position will not close the switch 47, and it will be necessary to close the door at least to the position shown in Fig. 2, before the cage can be moved. It is therefore necessary that all doors be closed before the cage can be moved.

If the locking collar 46 is held in an upright position the bores through the collars 50 will remain in alignment, and the plunger can be readily withdrawn by opening the door. In the present instance the means for holding the locking collar 46 against collar 44 comprises the electromagnet 10 having a coil 67, (Fig. 1). The electromagnet 10 is secured to the cage in such a position 55 that it will be as near to the lock as is possible without making any mechanical connection therewith, when the cage is at its landing. In the present instance, the electromagnet is secured to the cage by bracket 60 72. The lines of force which will emanate from said magnet when the coil 67 is excited will pass through the collars 44 and 65 45, and will hold the locking collar 46 in an

upright position. To facilitate and direct the flow of the lines of force from the magnet to the lock, the latter is provided with an adjustable conducting rod 68 which extends toward the former. This provision is 70 particularly desirable in elevators where the door sill extends into the hatchway for some distance, thereby necessitating an increased space between the electromagnet 10 and the locks 11. The electromagnet is provided 75 with a plate 69, held in a vertical position, which also acts as a magnetic conductor and as such governs the distance above and below the floor at which the door can be opened. It will be obvious that no door can 80 be opened unless the cage is before it with the electromagnet adjacent to the lock 11.

To excite the coil 67, the segmental contact 21 is moved to its central position onto contact 20, whereupon both electromagnetic 85 switches are opened and the motor stops. Consequently it is impossible to open any hatchway door while the cage is in motion, or in other words, until the power to the 90 elevator motor has been shut off.

If the current should fail, or if the electromagnet because of other reasons fails to perform its function, the operator can open the door to let out the passengers by using the emergency finger 53 to hold the 95 collar in an upright position. The elevator cage is so constructed that the operator has access to this emergency finger when the electromagnet is opposite the lock.

To allow the hatchway door on the first landing to be opened from the outside by authorized persons, the lock for that door may be equipped with an auxiliary electromagnet 70 which is rigidly secured there-to as shown in Fig. 10. This electromagnet 100 may be excited by closing a switch 71 in a special circuit therefor, said switch being adapted to be closed by such means as a special key. I have shown my invention as being especially adapted for use on elevator 105 hatchway doors but it should be understood that I do not wish to restrict its use to any one kind of application, for there are many other instances in which it can be used to advantage.

I desire to point out that while the invention has been herein illustrated and described with considerable particularity, I contemplate that various changes in form, construction and arrangement of parts may be 110 made by those skilled in the art, but without departing from the spirit and scope of the invention as expressed in the appended claims.

I claim as my invention:

1. In an electric elevator, in combination, 125 a hatchway, a door in said hatchway, a cage, an operating circuit for said cage, a lock for said door included in said circuit, a member coacting with said lock to retain 130

said door in a closed position, a withdrawal of said member from said lock acting to break said circuit, electromagnetic means for rendering said lock ineffective to retain 5 said member, a circuit for said electromagnetic; and a single control member for selectively closing said circuits.

2. In an electric elevator, in combination, a hatchway, a door in said hatchway, a cage, 10 a plunger on said door, a lock including a locking member for receiving said plunger, said locking member being movable into a position to retain said plunger upon an attempted withdrawal of the latter, and electromagnetic means carried by said cage for holding said member in an inoperative 15 position when adjacent said door.

3. In an electric elevator, in combination, a hatchway, a door in said hatchway, a 20 plunger on said door, a lock including a locking member for receiving said plunger, said locking member being movable to retain said plunger in said lock, and electromagnetic means for holding said member 25 in its inoperative position to allow a free withdrawal of said plunger.

4. In combination with a door, a plunger mounted on said door and having a plurality of notches, a casing for receiving 30 said plunger, a locking member in said casing for engaging any one of said notches when overlying it to retain said plunger in any one of a plurality of positions, and means for holding said member out of engagement with said notches.

5. In an electric elevator, in combination, a hatchway, a door in said hatchway, a lock for said door and including a switch, and a plunger mounted to enter said lock 40 and close said switch, said lock acting to retain said plunger in any one of a plurality of positions and said plunger serving to close said switch only when near its innermost position.

45 6. In an electric elevator, in combination, a hatchway, a door in said hatchway, a cage, a circuit which must be closed to cause the cage to travel, a lock for said door included in said circuit, and a member coacting with said lock to hold said door closed and to close said circuit so that elevator operation can be instituted.

7. In an electric elevator, in combination, a hatchway, a door in said hatchway, a 55 cage, a circuit which must be closed to cause the cage to travel, a lock for said door included in said circuit, a member coacting with said lock to hold said door closed and to close said circuit so that elevator operation can be instituted, and electromagnetic means cooperating with said lock after said circuit has been broken to allow a separation of said member and said lock.

60 8. In combination with a door, a plunger

mounted on said door, a casing for receiving said plunger, and means in said casing rendered movable to engage said plunger upon an attempted withdrawal thereof and prevent its complete withdrawal from said 70 casing.

9. In combination with a door, a plunger, a casing for receiving said plunger, and a locking member in said casing rendered operable by a partial withdrawal of the plunger from said casing to prevent its complete withdrawal therefrom.

10. In an electric elevator, in combination, a hatchway, a door in said hatchway, a 80 plunger secured to said door, a lock for receiving said plunger and acting to prevent a complete withdrawal thereof, and an emergency arm for allowing a complete withdrawal of said plunger.

11. In an electric elevator, in combination, a hatchway, a door in said hatchway, a plunger secured to said door, said plunger having a notch, a lock secured to said hatchway and having a locking member, said member allowing said plunger to freely 90 enter into mechanical engagement with said lock but acting to prevent a subsequent disengagement thereof, and means for holding said member inoperative so as to allow a severance of said mechanical relation.

12. In an elevator, in combination, a hatchway, a door in said hatchway, a plunger secured to said door, a lock secured to said hatchway for receiving and acting to retain said plunger, and means having no 100 mechanical connection with the lock, hatchway, or door for preventing said retention of said plunger.

13. In an electric elevator, in combination, a door, a plunger on said door, a lock 105 for receiving said plunger, a locking member in said lock, said lock acting to retain said plunger only through the action of friction and gravity upon said locking member.

14. In an electric elevator, in combination, a door, a plunger on said door and having a notch, and a lock for receiving said plunger, said lock having a locking member which under the influence of gravity engages 115 said notch whereby said plunger is retained within said lock.

15. In an electric elevator, in combination, a door, a plunger on said door, a lock 120 for receiving said plunger, said lock having a locking member which under the influence of gravity or friction acts to retain said plunger within said lock, and electromagnetic means for counteracting said influence to prevent said member from retaining said plunger.

16. In an elevator, in combination, a door, a plunger on said door, a lock for receiving said plunger, said lock having a locking member also for receiving said plunger,

said locking member moving to retain said plunger upon an attempted withdrawal of the latter, and means for preventing the movement of said member so as to allow said plunger to be withdrawn.

17. In an elevator, in combination, a door, a plunger secured to said door and having a notch, and a lock comprising a plurality of collars with their bores out of alinement, 10 said bores acting to receive said plunger whereby they are placed into alinement, and one of said collars engaging said notch; upon an attempted withdrawal of said plunger whereupon said bores are again out of 15 alinement.

18. In an electric elevator, in combination, a plunger having an insulated point, and a lock comprising a switch, and a locking member, said plunger entering said lock to 20 close said switch and said locking member acting to prevent the withdrawal of said plunger.

19. In an electric elevator, in combination, an electromagnet, a plunger having an 25 insulated point, and a lock comprising a

plurality of spaced collars, a movable collar between said first mentioned collar and normally being forced out of alinement therewith by gravity, and a switch, said plunger entering through said collars so 30 that its insulated point closes said switch and said movable collar acting to prevent the withdrawal of said plunger.

20. In combination with a door, a plunger on said door, a lock for receiving said plunger and for preventing a withdrawal thereof, and means cooperating with said lock to allow said plunger to be withdrawn, said lock necessitating no movement of its parts 35 to allow the door to be opened.

21. In combination with a door, a plunger on said door, a locking means comprising an apertured member and a locking collar within said member, said locking means acting to receive and retain said plunger, 40 and electromagnetic means for preventing said retention.

In testimony whereof, I have hereunto affixed my signature.

JOHN F. CLANCY.
